CLAIM

We claim the ornamental design for a gauge, as shown and described.

DESCRIPTION

FIG. 1 is a perspective view of a gauge embodying the invention;

FIG. 2 is a front view of the gauge of FIG. 1; and,

FIG. 3 is a left side view of the gauge of FIG. 1.

The thick broken lines showing the instantaneous speed markings and the thin broken lines showing the rear case

(Continued)

structure are provided for the purpose of illustrating portions of the article and forms no part of the claimed design.

1 Claim, 2 Drawing Sheets
